DESIGN FOR A SCAFFOLD FRAME

Lawrence C. Oertle, Sr., Milwaukee, Wis.

Application April 25, 1945, Serial No. 119,179

Term of patent 14 years

(Cl. D54—1)

To all whom it may concern:

Be it known that I, Lawrence C. Oertle, Sr., a citizen of the United States of America and a resident of Milwaukee, in the county of Milwaukee and State of Wisconsin, have invented a new, original, and ornamental Design for Scaffold Frame, of which the following is a specification, reference being had to the accompanying drawing, forming a part thereof.

In the drawing:

Fig. 1 is a top view of the scaffold frame showing my new design;

Fig. 2 is a side view of the scaffold frame; and
Fig. 3 is an end view of the scaffold frame.

I claim:

The ornamental design for a scaffold frame, as shown.

LAWRENCE C. OERTLE, SR.
